UNITED STATES PATENT OFFICE.

FREDERICK H. SPRAGUE, OF ORANGE, MASSACHUSETTS.

CHILD'S GARMENT.

No. 877,607.

Specification of Letters Patent.

Patented Jan. 28, 1908.

Application filed November 20, 1906. Serial No. 344,318.

To all whom it may concern:

Be it known that I, FREDERICK H. SPRAGUE, a citizen of the United States, residing at Orange, county of Franklin, and State of Massachusetts, have invented an Improvement in Children's Garments, of which the following description, in connection with the accompanying drawing, is a specification, like letters on the drawing representing like parts.

10 This invention relates to one-piece children's garments such as are commonly known as "play-suits." These garments comprise a waist portion and a trousers or pants portion which are sewed together so that the garment is a one-piece garment.

15 It has heretofore been proposed to improve the looks of these garments by producing a blouse effect in the waist, and one of the ways in which this blouse effect has been produced 20 has been by the use of straps or bands which are fastened to the waist at the shoulder thereof and which extend down to the waist-band both at the front and the rear, said straps being of the proper length to take the weight of 25 the trousers so that the material of the waist will blouse more or less.

While the strap arrangement above described is effective in securing the blouse effect, yet the entire weight of the trousers portion of the garment comes directly on these straps. I have improved this class of garment by eliminating the straps above referred to and by using a lining for producing the blouse effect, which lining is preferably reinforced at suitable points, as, for instance, at 30 the center in the front, at each side and in the back.

35 In the drawings wherein I have shown one embodiment of my invention, Figure 1 is a back view of a garment embodying my invention; Fig. 2 is a front view of the garment; Fig. 3 is a section on the line $x-x$, Fig. 1.

The waist portion of the garment is designated by 2 and the trousers portion by 3. 40 These two portions are sewed together at the front, as at 4, and the waist is arranged to open in the back as usual in this class of garments. The trousers portion is also provided at its rear with a flap 5 which is provided with 45 buttonholes to be buttoned to the back side of the waist portion. The construction thus far described is such as is commonly found in 50 garments of this class.

In order to produce the desired blouse effect to the waist, I employ a lining 6; the up-

per end of which is secured to the neck of the waist along the line 7, and the lower end of which is secured to the waist band of the waist, as at 8. Preferably also the lining is sewed to the waist along the shoulder seam 60 by a line of stitching 9, which line of stitching may be the stitches of the shoulder seam itself, and said lining may also be sewed to the waist around each arm scye, as at 10. The lining, however, is disconnected from the 65 waist at other portions thereof.

The lining is made somewhat shorter than the material of the waist so as to produce a fullness or blouse effect in the waist, as shown at 11 in Fig. 2, and if desired this 70 effect may be augmented by gathering the front of the waist, as at 12, when it is sewed to the trousers. The amount that the waist 11 is bloused or the fullness thereof will depend upon the relative lengths of the lining 75 and the waist, and by making the waist considerably longer than the lining a greater blouse effect can be produced.

The lining may be secured to the waist by the lines of stitching 16 which secure the 80 waist to the trousers, or by separate lines of stitching and preferably suitable tabs 17 will be inserted between the lining and the waist and sewed thereto, said tabs constituting a means for attaching hose supporters. 85

Garments of this class are most commonly used as summer garments, and it is therefore desirable that they should be comparatively thin. If a thin lining is employed the strain 90 thereon is apt to tear it, and in order to give the lining sufficient strength to maintain the blouse effect without making it unduly thick I have provided a system of reinforcing the lining at various points where it is subjected to strain. 95

As illustrated in the drawings the lining is reinforced at the center, in front, at each side from the arm-scye down to the waist and at the back.

At the center of the garment in the front 100 thereof I employ a reinforcing piece or band 13 which extends from the neck to the waist-band thereof. At each side I employ other reinforcing bands 14 which extend from the arm-scye to the waist-band, and at the back 105 I employ still other reinforcing bands 15, one at either edge of the lining, which reinforcing pieces 15 also extend from the collar to the waist-band. These reinforcing bands are preferably stitched to the lining through- 110

out their length, thus making the bands part of the lining.

One advantage of my garment over that in which loose bands or straps are used for obtaining the blouse effect is that there are no loose bands or straps to interfere with the insertion of the arms of the wearer into the sleeves of the garment, and the inside of the garment is free from bunches or seams which are likely to chafe or irritate the wearer.

Having fully described my invention, what I claim as new and desire to secure by Letters Patent is:—

1. A garment comprising a connected waist portion and trousers portion, the waist portion opening in the back, a lining connected to the waist portion at the neck thereof and at the waist band, said lining being shorter than the material of the waist, whereby a blouse effect is produced, and reinforcing bands stitched to the lining, one band extending from the neck thereof to the waist band in front and others extending

from the arm scye to the waist band at each side.

2. A garment comprising a connected waist portion and a trousers portion, the waist portion opening in the back, a lining connected to the waist portion both at the neck thereof and at the waist-band and along the shoulder seams, said lining being shorter than the material of the waist, whereby a blouse effect is produced, said lining being reinforced at the front of the garment, from each arm-scye to the waist-band and at each edge thereof at the back, and tabs 17 secured to the waist-band inside of the trousers for the attachment of hose supporters.

In testimony whereof, I have signed my name to this specification, in the presence of two subscribing witnesses.

FREDERICK H. SPRAGUE.
